PISTON DRILL GUIDE BLOCK

Raymond M. Ulrich, Shelbyville, Ill., assignor to
Alois W. Graf, Strasburg, Ill.

Application December 21, 1938, Serial No. 247,088

7 Claims. (Cl. 77—62)

My invention relates to piston drill guide blocks, and more particularly to piston expander drill guide blocks which cooperate with the slot of the expansible piston skirt.

5 This application is a continuation-in-part of my copending application Serial No. 204,272, filed April 26, 1938, entitled "Piston expanders and method of installation."

Heretofore, numerous piston expanders and 10 expansible pistons have been proposed. Such devices, however, have often been characterized by a complex structure which necessitated special machining of the piston and special tools for the installation of such devices. It, of course, would 15 be desirable to provide a simple piston expander suitable for pistons of various sizes and of different thicknesses of piston walls which would serve to produce an expansion fit within the piston cylinder without the use of special adjustable devices.

20 It is, therefore, an object of my invention to provide an improved piston expander and method of installation which will overcome many of the disadvantages inherent in the devices of the prior art and which will be simple and reliable 25 in operation.

A further object of my invention is to provide 30 an improved piston drill guide block and method of preparation of expansible pistons for the reception of a piston expander cooperating with the piston block of the expansible skirt.

It is a still further object of my invention to 35 provide an improved piston drill guide block and method of preparation of expansible pistons for the reception of a piston expander which will produce the same degree of expansion fit within the piston cylinder in the case of thick-walled pistons, as is the case in thin-walled pistons.

A still further object of my invention is to 40 provide a new and improved drill guide block for producing indentations in the faces of the slot of a piston which have surfaces which are oblique sections of a cylindrical surface.

The novel features which I believe to be characteristic of my invention are set forth with particularity in the appended claims. My invention itself, however, both as to its organization and method of operation, together with further objects and advantages thereof, will be understood better by reference to the following description taken in connection with the accompanying drawings in which Figs. 1 and 2 show one embodiment of my piston expander; Figs. 3 and 4 show alternative embodiments of my piston expander; Fig. 5 shows an exterior view of

a piston skirt provided with my expander; Fig. 6 shows a perspective view of my piston drill guide block; Fig. 7 shows the application of my drill guide block to the skirt of a piston; Figs. 8 and 9 explain the operation of the drill guide block in connection with thin walled pistons; Figs. 10 and 11 explain the operation of the drill guide block in connection with thick-walled pistons; Fig. 12 shows a perspective view of another type of piston expander; Fig. 13 shows a perspective view of another type of piston drill guide block; Fig. 14 shows the application of this modified form of drill guide block to the slot of a piston skirt; Fig. 15 explains the operation of the drill guide block in connection with thin-walled pistons; Fig. 16 explains the operation of the drill guide block in connection with thin-walled pistons; Fig. 17 shows the expander of Fig. 12 inserted in a piston.

Referring to Figs. 1 and 2 of the drawings, I have illustrated therein one embodiment of my piston expander comprising an arcuate shaped body member 1 preferably of spring steel, provided with a plurality of projections or lugs 2 in the proximity of the ends of the body 1 and a projection or lug 3 at an intermediate portion thereof. The projections 2 near the ends of the body 1 are set back from the extremities thereof so as to leave flat portions 4, the purpose of which will subsequently become apparent. The projecting members 2 and 3 are arranged substantially perpendicular to the plane of the arc of the body of the expander, but preferably at slight angles to the perpendicular of the plane so that the curved outer portions of the projections 2 and 3 form slight angles to the right and left of a line perpendicular to the plane of the arc of the body member 1.

In Fig. 3 there is shown a modification of my piston expander which is made of thinner material and the projections thereof have convex bearing surfaces and concave inner surfaces. In this figure those portions of the expander corresponding to Figs. 1 and 2 have been given the same reference characters together with the subscript *a*. In Fig. 4 a still further modification of my invention is shown in which parts corresponding to the expander shown in Figs. 1 and 2 have been given similar reference characters, together with the subscript *b*. In this instance, however, the member 1_b is arcuate in one direction through the greater portion of its length and near the extremities thereof the member 1_b is bent over in the reverse direction in a U shape. Thus, in this embodiment the

flat portions of the expander corresponding to 4 in the Figures 1 and 2 and to 4a in Figure 3 are now displaced to points on the opposite side of the projections 2b as indicated by the flat surfaces 4b in the figure. If desired, the curvature of the body member 1b may be such that the projections 2b and 3b are in the same relative positions as the projections 2 and 3 of Fig. 1. Each of the projections in these two figures are also placed at slight angles to the perpendicular to the plane of the curvature of the body members 1a and 1b. While the expanders shown in Figs. 1 to 4 have been illustrated as each having three projections, it will of course be apparent to those skilled in the art that a greater or lesser number of projections may be utilized since it is only necessary to have the concave bearing surfaces of the projections at acute angles to a plane perpendicular to the plane of the body members, or at acute angles to a plane perpendicular to a plane which is tangent to the curvature of the piston skirt at the slot. The projections at these angles are arranged so as to cooperate and be complementary to indentations in the faces of the slot of the piston skirt.

Fig. 5 discloses a piston having an expandable skirt provided with a slot therein. The faces of the slot have indentations therein which have surfaces corresponding to oblique sections of a cylindrical surface. The expandable piston skirt 5 which is normally provided with a slot 6 having indentations 7 on the faces thereof is shown with an expander of the type disclosed in Figs. 1 and 2 arranged within the piston skirt 5 and having projections 2 and 3 extending into the indentations 7. The flat end portions 4 of the body member 1 of the expander serve as bearing surfaces adjacent the inside wall of the piston skirt thereby preventing a possible change in the position or shape of the expander, due to temperature variations which would tend to cause the end projections 2 to extend to the wall of the piston an undesired amount. The flat portions 4 and the body member 1 are therefore contiguous to the inside wall of the piston skirt.

It of course will be apparent that expanders of the type shown in Figs. 3 and 4 can likewise be utilized in a manner similar to that shown in Fig. 5. Due to simplicity of the expander it will be found that the expander is adaptable to all types of piston, regardless of the inside shape of the piston, with reference to strengthening struts and ribs.

Reference may now be had to Fig. 6 in which I have shown a piston drill guide block comprising an elongated body portion 8 having a concave face 9 the radius of curvature of which corresponds approximately to the radius of curvature of the pistons more commonly in use. This concave surface 9 is provided with a pair of projections 10 and 11 located adjacent opposite ends of the elongated body portion 8 so as to engage the slot 6 of the piston skirt 5 shown in Fig. 5. At one extremity suitable fastening means are provided comprising a head member 12, a flat portion 13, a threaded portion 14 and a nut 15 which serves to maintain the block 8 in proper operative position on the piston skirt. The head member 12 bears against the inside surface of the piston skirt while the flat portion 13 is located between the faces of the piston slot. The body portion 8 is furthermore provided with a plurality of drill bit guides 16, 17 and 18, respectively, which are spaced apart and extend from the concave surface 9 through the block, the axis of each guide

forming an acute angle with the perpendicular to the tangent of the curvature of the concave face 9 at the center line extending between the projections 10 and 11. The alternate axes of the members 16, 17 and 18 are so placed to the right and left of the center line that the drill bit cooperating within the guides will produce indentations in the faces of the slot which are sections of a cylindrical surface each defined by planes which are oblique angled with respect to the axis of said surface. Fig. 7 shows the drill guide block 8 in operative relation with respect to the piston skirt 5 and from this view it is apparent that the axes of the drill bit guides 16 and 18 are in the same plane which is at an acute angle to the right of a plane perpendicular to a plane tangent to the curvature of the piston skirt at the slot, whereas the axis of the drill bit guide 17 is in a plane which is at an acute angle to the left of the plane perpendicular to a plane tangent to the curvature of the piston skirt 5 at the slot.

From Figs. 8 and 9, which are respectively sectional views along the lines A—B and C—D of Fig. 7, it will be seen that in a thin-walled piston skirt the inside view of the arcuate indentations in the faces of the slot would present indentations in staggered relation so that if tangents to the indentations were drawn on the inside of the skirt parallel to the faces of the piston slot 6, they are spaced apart an appreciable amount. Thus, in a thin-walled piston skirt expanders of the type shown in Figs. 1, 2 and 3 do not exert as great a tension on the piston skirt as would be the case in thick-walled piston skirts. Figs. 10 and 11 are sectional views respectively along the lines A—B and C—D of Fig. 7 in the instance where thick-walled pistons are utilized. In this instance it will be apparent from the figures that when viewed from the inside of the piston skirt the arcuate indentations will appear to be more nearly in line and hence if tangents to the indentations are drawn parallel to the piston slot on the inside of the piston skirt, these tangents will be closer together than was the case in a thin-walled piston. Thus an expander such as shown in Figs. 1, 2 and 3, when inserted in the indentations thus made will exert a greater force on a thick-walled piston than on a thin-walled piston. The angles at which the drill bit guides 16, 17 and 18 have been arranged are so chosen that any expander of the type shown in Figs. 1, 2, 3 and 4 will always produce the proper biasing effect against the slot faces at the indentations to produce the proper expansion fit of a piston within the piston cylinder. From this it is apparent that the single type of piston expander produces the proper expansion in both thin-walled and thick-walled piston skirts. Thus no compensation or adjustment is required on the part of the person installing these expanders to provide for the variation in the thickness of piston walls.

While for the purpose of illustration the drill bit guide blocks shown in Figs. 6 to 11 have been shown of the type having three guides therein, it of course will be apparent to those skilled in the art that a greater or lesser number of guides may be utilized in accordance with the number of projections on the type of expander to be installed. This will be apparent to those skilled in the art when it is remembered that the guides each are at a slight angle to a plane perpendicular to a plane tangent to the curvature of the

piston skirt at the slot or tangent to the curvature of the drill guide block.

This is illustrated in Fig. 12 of the drawings wherein I have shown another embodiment of a piston expander comprising a body member 19 arranged in a double reverse curve shape or, in other words, a shape having a central U or horse-shoe-shaped portion and the ends of the U or horseshoe-shaped portion are bent back in reverse curves. Near the ends 20 of the curved portion of the expanders there are small portions 21 substantially at right angles to the ends 20 and at right angles to the small portions 21 there are projections 22 which have convex bearing surfaces. The projections 22 are arranged to engage indentations along the faces of the piston slot and the flat portions 21 serve as inside bearing surfaces on the inner face of the piston skirt. If, at the center of the convex surfaces of the projections 22 planes are drawn tangent thereto it will be found that the planes of the two projections 22 will form an acute angle the vertex of which will be on the inside of the piston. The projections 22, therefore, may be said to be at acute angles to each other and at acute angles to a plane perpendicular to the plane of the body 19 of the expander.

In Fig. 13 I have shown a piston drill guide block having a body portion 23 which has a concave shape 24, the radius of curvature of which corresponds approximately to the radius of curvature of the pistons more commonly in use. At the upper end of the concave surface 24 there is provided a projection 25 for the purpose of engaging the slot of the piston skirt. At the other extremity of the body 23 suitable fastening means are provided comprising a head member 26, a flat portion 27, a threaded portion 28 and a nut 29 which serves to maintain the block 23 in proper operative relation on the piston skirt. The head member 26 bears against the inside surface of the piston skirt while the flat portion 27 is located between the faces of the slot. The body portion 23 is furthermore provided with a plurality of drill bit guides 30 and 31, respectively, which are spaced apart and extend from the concave surface 24 through the block 23, the axis of each guide forming an acute angle with the perpendicular to the tangent of the curvature of the concave face 24 at the center line extending between the projection 25 and the aperture for the fastening means 26 to 29. The axes of the guides 30 and 31 are so placed to the right and left of the center line that the drill bits cooperating within the guides will produce indentations in the faces of the slot which are oblique sections of a cylindrical surface.

In Fig. 14 I have shown a portion 32 of the piston skirt, a piston skirt slot 33 and another portion of a piston skirt 34. The drill guide block 23 is shown in opposite relation with respect to the piston slot 33. From this view it will be apparent that the axes of the drill bit guides 30 and 31 have a common plane which is substantially at right angles to the piston slot 33. If planes along the axes of the drill bit guides 30 and 31 are formed which are perpendicular to the common plane it will be found that these planes form an acute angle somewhere to the inside of the piston skirt.

Fig. 15 shows a sectional view along the line E—F of Fig. 14 in the instance where a thin-walled piston skirt is used. From this view it will become apparent that the arcuate indentations in the faces of the slot when viewed from

the inside of the piston skirt are spaced apart an appreciable amount. If tangents to the indentations were drawn on the inside of the skirt parallel to the faces of the slot 33 they would be spaced apart an appreciable amount. Thus in a thin-walled piston skirt the expanders of the type shown in Fig. 12 will not exert as great a tension on the skirt as would be the case in thick-walled piston skirts.

Fig. 16 shows a sectional view along the line E—F of Fig. 14 in the instance where thick-walled pistons are utilized. In this instance it will be apparent from the figure that when viewed from the inside of the piston skirt the arcuate indentations will appear to be closer together and hence if an expander such as shown in Fig. 12 is inserted in the indentations, it will exert a greater force on a thick-walled piston than on a thin-walled piston. The angles at which the drill bit guides 30 and 31 have been arranged have been so chosen that any expander of the type shown in Fig. 12 will always produce the proper biasing effect against the slot faces of the indentations to produce the proper expansion fit of the piston within the piston cylinder.

Fig. 17 illustrates the manner in which an expander of the type shown in Fig. 12 is inserted in the indentations 35 which are formed in both of the faces of the piston slot 33 by the drill bits cooperating in the guides 30 and 31. It will be seen that the convex surfaces of the expander projections 22 are complementary to the arcuate indentations 35 which have concave surfaces each comprising oblique sections of a cylindrical surface.

While I have shown and described my invention in connection with certain specific embodiments, it will, of course be understood that I do not wish to be limited thereto, since it is apparent that modifications may be made in the instrumentalities employed without departing from the spirit and scope of my invention as set forth in the appended claims.

What I claim as new and desire to secure by Letters Patent of the United States is:

1. A drill guide block for cooperation with a slotted piston skirt comprising a block having a concave surface provided with projecting means thereon for engaging the slot of said piston skirt, and a plurality of drill bit guide apertures extending from said concave surface through said block, the axis of each guide aperture forming an acute angle with the perpendicular to the tangent of the curvature of said concave surface at the point of intersection of said guide aperture therewith.

2. A drill guide block for cooperation with the slot of an expansible piston skirt comprising a block having a concave face adjacent said piston skirt, means on said concave face for engaging said piston slot, there being a plurality of drill bit guides extending from said concave face through said block, the axis of each guide forming an acute angle with the perpendicular to the tangent of the curvature of said piston skirt at said slot, the axes of said guides being to the right and left of the center line of said slot whereby the drill bit cooperating within said guide will produce indentations in the faces of said slot so that tangents thereto parallel to said slot face on the inside of said skirt are closer together in thick-walled pistons than in thin-walled pistons.

3. A drill guide block for cooperation with a

- slotted piston skirt comprising a block having a concave surface adjacent to the outer curved surface of said piston skirt, means provided on said concave surface for engaging said slot of said piston skirt, there being a plurality of drill bit guide apertures extending from said concave surface through said block, the axis of each of said guides forming an acute angle with the perpendicular to the tangent of the concave surface at the intersection of said aperture therewith whereby drill bits operating within said guide apertures will produce in the faces of said piston slot indentations each of which comprise sections of a cylindrical surface formed by planes which are oblique angled relative to the axis of said slot.
4. A drill guide block for cooperation with a piston skirt having a slot therein, said drill bit guide block having a plurality of drill bit guides arranged to have their axes in two planes, said planes being at acute angles to the right and to the left of a plane perpendicular to the tangent of the curvature of said piston skirt at said slot whereby drill bits cooperating with said guide will produce indentations in the faces of said slot which have surfaces comprising sections of a cylindrical surface formed by planes which are oblique angled relative to the axis of said surface.
5. A drill guide block for cooperation with the slot of an expansible piston skirt comprising a block having a concave face adjacent said piston skirt, means on said concave face for engaging said piston slot, there being two drill bit guides extending from said concave face through said block, the axes of said guides being in a plane perpendicular to said piston block, the axes of said guides forming an acute angle the vertex

of which is to the interior of said piston skirt whereby drill bits cooperating within said guide will produce in the faces of said piston slot indentations each of which comprise sections of a cylindrical surface formed by planes which are oblique angled relative to the axis of said surface.

6. A drill guide block for cooperation with the slot of an expansible piston skirt comprising a block having a concave face adjacent said piston skirt, means on said concave face for engaging said piston slot and for maintaining said block in operative position, there being two drill bit guides extending from said concave face through said block, the axes of said guides being in a plane perpendicular to said piston slot and forming an acute angle the vertex of which is to the interior of said piston skirt whereby drill bits cooperating within said guide will produce an indentation in each of the faces of said slot so that the indentations when viewed from the inside of said skirt are closer together in thick-walled pistons than in the thin-walled pistons.

7. A drill guide block for cooperation with a slotted piston skirt comprising a block having a concave surface adjacent to the outer curved surface of said piston skirt, there being a plurality of spaced apart drill bit guides the axes of which are arranged at acute angles to the right and to the left of a plane perpendicular to the tangent of the curvature of the said piston skirt at said slot whereby drill bits cooperating within said guide will produce spaced apart indentations in the faces of said slot which have surfaces comprising sections of a cylindrical surface formed by planes which are oblique angled relative to the axis of said surface.

RAYMOND M. ULRICH.
